UNITED STATES PATENT OFFICE.

JAMES S. DONNELLAN, OF SALT LAKE CITY, UTAH.

JAW-CLOSER.

1,358,625.

Specification of Letters Patent.

Patented Nov. 9, 1920.

Application filed May 31, 1919. Serial No. 300,876.

To all whom it may concern:

Be it known that I, JAMES S. DONNELLAN, a citizen of the United States, residing at Salt Lake City, in the county of Salt Lake 5 and State of Utah, have invented certain new and useful Improvements in Jaw-Closers; and I do hereby declare the following to be a full, clear, and exact description of the invention, such as will enable others skilled in the art to which it 10 appertains to make and use the same.

This invention relates to mechanical dentistry, and especially to improved maintaining attachments for the base mountings of 15 artificial teeth, commonly known in the art as jaw closers.

In a former patent #1,263,313 of April 16, 1918, I have disclosed and claimed certain peculiarly formed and novelly connected springs functioning, in an automatically self-compensating manner and for the purposes as therein fully set forth; and while the instant invention also has the same broad principles in view, it has been primarily devised with reference to the manner 25 of connecting the ends of the springs to their supporting bases, to provide regulable means for adjustably controlling the disposition, lines of thrust, and tension thereof.

Supplemental to this broad statement, the 30 objects and advantages of the detailed construction, assembly and functioning of the several elements, of the present combination, will otherwise be so clearly apparent, as incidental to the following description, that it 35 would only be undesirable surplusage to further refer to them initially.

Reference will be had, therefore, to the 40 accompanying drawings, illustrating a practical embodiment of the improvements, in which drawings—

Figure 1 is a side elevational view embodying the invention as applied to an artificial pair of upper and lower full dentures; 45 Fig. 2 is an analogous view, but showing the upper regulable keeper-disk adjusted to a different position to that shown in Fig. 1; Fig. 3 is a detail elevational view of one of the spring members in its unattached distended position; Fig. 4 is a local 50 sectional view taken in the plane of the line 4 of Fig. 1; Figs. 5 and 6 are detail front elevational and top edge views of one of the keeper-disks; Fig. 7 is a cross-sectional view thereof along the line 7 of Fig. 5; 55 and Figs. 8 and 9 are side elevational and

top edge views, respectively, of one of the spring members, but with its ends bent at slightly different angles to the showing in Fig. 3.

For simplicity and brevity of disclosure, I shall only illustrate and describe the invention as associated with complete sets of artificial teeth, as in full upper and lower dentures, but it should be distinctly understood at the outset that the invention is also susceptible for efficient use with blocks of teeth or partial dentures, and whether or not the artificially adjusted denture is associated with analogous artificially mounted teeth, or with natural teeth in an upper or lower row in the mouth of the user, and I do not, therefore, limit myself in such respects.

The numerals 1 and 2 respectively designate the composite gum bases, mounting the upper and lower sets of teeth, formed and employed as is customary to snugly seat over the natural gums, and 3 generally designates the improved connections therebetween, which are congruently disposed as a pair with one spring member located exteriorly at the sides of each gum base.

These connecting spring elements, for best results both as to functioning and comfort, should be constructed and attached substantially as shown, in order to avoid any bulkiness and sharp edges, while at the same time providing for the proper flexible motion laterally as well as vertically, thus 85 permitting of coördinate action with the normal movements of the lower jaw, and hence a more natural articulation of the teeth.

Each spring element preferably comprises 95 a proper length of wire, suitable as to resiliency and tensile strength, which is successively coiled upon itself to provide a body portion, intermediate of elongated extending ends, embodying a continuous series 100 of springy rings or integral link-eyes 8, lying flatwise in substantially the same longitudinal plane analogously to my former patent. As at present devised, however, these link-eyes 8, instead of being disposed 105 practically edgewise, are now more compactly arranged to just slightly overlap each other, while still leaving the coils freely open or unobstructed laterally. The elongated ends, which also extend in the plane 110 of the series, provide the idle-eyes 6 and 10, substantially separated from the link-eyes

8 by the spacing segments 7 and 9 respectively, and likewise the spacing arms 5 and 11, respectively, furnish offsetting means for one terminal attaching eye 4 and for a 5 springy fulcruming eye 12, from which latter coiled eye 12 the wire is projected inwardly, at a substantial angle to the periphery thereof, to function as a short lever arm 13 terminating in the pivotal attaching eye 14 at the other end of the spring element, as shown detached in Figs. 3, 8 and 9.

15 designates pivot pins, headed as at 16 at one end and screwthreaded at the other end, of which pins one is embedded and 20 anchored in the gum bases 1 and 2, at each side, with the threaded end projecting exteriorly thereof. 18 designates the hollow shank of a securing button, in the nature of a finishing cap, which shank is internally threaded to coöperate with the threaded end of the pivot pins, the convex head 19 of the button being slotted as at 20, for applying a spanner device for loosening and tightening purposes, all of which features are substantially the same as in my former patent 25 and as shown in detail herein at Fig. 4; but the manner of adjustably regulating the mounting of the attaching terminal eyes 4 and 14 on their respective pivot pins 15 is 30 distinctively different.

As to this latter feature I now additionally employ regulating disks or washers 21, centrally apertured at 22 for rotatable mounting, one each on each pivot pin 15, between a gum base and a complementary pivotal attaching eye 4 or 14, and which disks are provided with a segmental keeper 23 offset from its disk, by the spacing stud continuations 24, to provide for a containing 35 and confining space 25 for the spring ends, pivotally associated with the gum bases as seen in detail at Fig. 4.

The terminal attaching eyes 4 and 14 do not actually engage the pivot pins 15, but 40 freely encircle the hollow shank 18 of a complementally associated securing button, the inner ends of which shanks also serve as set screw elements, operatively engaging the opposed outer faces of the adjustable regulating keeper disks 21 to securely bind the latter as seated up against their respective gum bases.

It is to be noted that the attaching eyes 4 and 14, and hence the spring members as a 55 whole, are held spaced from the gum bases by being interposed between the regulating disks 21 and the heads of the securing buttons, with the terminal ends of the spring elements confined within the spaces 25, 60 formed with the disks by their keeper member 23; also that the lever arm 13 and all of the coils of the spring members (excepting in Figs. 8 and 9 where a slight bending of the ends is provided for) lie in the same 65 longitudinal plane, or in planes so closely

contiguous as to be substantially the same plane, whereby the structural formation is in the nature of an elongated flat spring, tensioned to spring edgewise along its whole length, with the freely open convolutions 8 70 serving as intermediately overlapped and integrally joined flexible link-eyes, as contradistinguished from a helicoidal spring flexed along the axis of its spirals.

Of course, where one of the sets of teeth 75 is natural, the manner of anchoring the pivot pins 15 would manifestly have to be altered, but without encumbering the drawings with unnecessary illustrations, the same principle exactly would be involved by simply projecting short threaded pivot pins 80 from any suitable metallic base supported for instance by crowned natural teeth. In such cases as just stated, the mounting of the levers 13 would naturally be associated 85 with the artificial set, whether upper or lower as occasion might require, which would prevent the levers 13, in their oscillating movements, from engaging and irritating the natural gums by rubbing thereon, 90 although this would be substantially avoided anyhow by the clearance provided for by the interposed keeper disks. However, where both sets are artificial, it may be preferable to locate the levers 13 on the 95 upper set, where food is less liable to lodge and obstruct their freedom of movement.

At any event, as in my former patent, the lever elements 13, each having the shiftable springy fulcruming eye 12 offset or distant 100 from its pivotal pin 15, provide for full clearance spaces, at all times, between the pair of chain springs and all of the teeth; but in the present case the supplemental feature of the regulating keeper disks serves 105 a further important advantage, in their varying adjusted positions, of positively controlling the disposition, lines of thrust and tension of the self-compensating springs, as is clearly illustrated by a comparison of 110 Figs. 1 and 2 of the drawings.

In both of these views, the lower disks 21 are set at the same operative positions, while the upper disk shown in Fig. 2, with its keeper element 23, has been rotated and 115 set at a different position to that of Fig. 1, illustrating a varied adjustment of the bowed springs. Likewise, the lower disks may also be set at any desired positions, and the pressure of the springs thus regulated 120 to an extreme nicety, not heretofore accomplished. Obviously, this is accomplished by simply loosening or easing up on the securing buttons and then, after turning the disks 125 as desired, tightening up these binding members again.

The offsetting stud arms 24 of the keeper elements also serve as thrust bearings for the lower ends of the springs, and partly so for the upper ends thereof, while at the same 130

time functioning as limiting stops to the swing of the short lever arms 13; and the segmental arms 23 of the upper and lower disks coöperate in pairs as lateral guides or 5 guards for maintaining the bowed springs properly disposed during the grinding motions of the lower jaw.

It will be observed that, whether the 10 spacing section 5, of the lower ends of the springs, is continued straight out from the section 7, as indicated in Figs. 1 to 3, or is bent as in Figs. 8 and 9, it always seats firmly down on the lower stud arm 24 of the keeper part, of its regulator disk, conjointly 15 functioning therewith as a throw or thrust bearing for the spring body, thus avoiding the rigid fastening of the lower ends of the springs as heretofore; and another purpose of this bottom end arrangement is that, 20 should the top set of teeth have a narrow strip of rubber, as sometimes employed, so that the spring would tend to protrude vertically beyond the gum bases, this may be overcome by bending the part 5 down, say 25 at an angle of about forty-five degrees, and likewise altering the angle of the lever arm 13 if found desirable, and this whether or not slight lateral bends are made also, as indicated in Fig. 9, all of which bendings 30 will be fairly apparent as obvious manipulations of proper attachment, provided for, however, by the particular formation of the spring ends.

When the jaws are fully closed, as indicated at Figs. 1 and 2, the levers 13 lie in their forward positions as far as permitted by their regulating disks, the thrust on the upper denture being in an upward and slightly forward direction, while that on the lower one is almost directly downward. During the opening and closing motions of the lower jaw, the spacing arms 5 necessarily still remain seated firmly in their keeper elements as the levers 13 ride rearwardly 45 and forwardly in their keeper guides, the thrust on the upper denture being then approximately in an upwardly direct vertical manner, provided for by the shifting fulcruming eyes 12, while that of the lower denture is in a downward and slightly rearward direction, the hinging movements of the lower jaw being fully compensated for by the pair of springs, and the lines of thrust and tensioning of the springs being also 50 regulable, to the minutest degree or nicety of adjustment, by varying slightly the positions of the keeper-disks 21, it being obvious that the compression of the springs as in Fig. 2 proportionately increases their 55 tension over the position shown in Fig. 1.

There is therefore assured an evenness or uniformity of regulable pressure, even during the movement of the lower jaw from the closed to the open position and 60 vice versa, which desired pressure is equal-

ized and maintained by reason of the particular construction and mounting of the resilient elements 3, as hereinbefore emphasized, and these novel details are of no mean importance, where efficiency of action, comfort and cleanliness are so greatly concerned.

While I have thus made a full and complete disclosure of my improvements as now practised, obviously minor modifications might be made without departing from the underlying principles of the invention, and it will be understood, therefore, that I do not limit myself necessarily to the exact details as illustrated and described, excepting as they may come within the purview of the ensuing claims, when fairly interpreted in the light of the specification and understood equivalents.

I claim—

1. In applied mechanical dentistry, providing jaw closer attachments embodying a pair of elongated springs suitably formed and disposed to function in the mouth of the user substantially as set forth, with one end of each spring pivotally supported and their other ends suitably mounted in respective complementary association with opposed gum bases; the employment of a rotatably mounted and adjustable tension regulating member coöperatively engaging each of said pivotally supported spring ends, for controlling the bowed compression of said springs, substantially as described.

2. In applied mechanical dentistry, providing jaw closer attachments embodying a pair of elongated springs suitably formed and disposed to function in the mouth of a user substantially as set forth, with means for suitably mounting one end of each spring in association with one gum base and a pair of pivot pins projecting outwardly from opposite sides of the other gum base, for pivotally mounting the other ends of said springs; the combination of a pair of rotatably adjustable tension regulating members, one of which is mounted on each of said pivot pins and carries a keeper element encompassing and engaging its adjacent pivotally supported spring end; and a capping head for each of said pivot pins, having a shank functioning both as a bearing sleeve for its adjacent spring end and as a binding element for the complementary tension regulating member, substantially as described.

3. In applied mechanical dentistry, providing jaw closer attachments embodying a pair of elongated springs suitably formed and disposed to function in the mouth of a user substantially as set forth, with pivot pins mounted in pairs at opposite sides of and having threaded ends projecting outwardly from the upper and lower gum bases, being adapted to pivotally mount the ends

of the said springs; the combination of a rotatably adjustable tension regulating disk mounted on each of said pivot pins and each carrying a side-offset segmental keeper encompassing and engaging its adjacently pivoted spring end, whereby all of said spring ends are under adjustable regulation for controlling the bowed compression of said springs; and a capping head threaded on

each of said pivot pins and each having a shank functioning both as a bearing sleeve for its adjacent spring end and as a binding element for engaging its complementary tension regulating disk, substantially as described.

In testimony whereof, I affix my signature.

JAMES S. DONNELLAN.
